United States Patent [19]

Tsubokura et al.

[11] Patent Number: Des. 316,081

[45] Date of Patent: ** Apr. 9, 1991

[54] CONNECTOR HOUSING FOR A NOISE ELIMINATOR

2308219 11/1976 France 439/350

[75] Inventors: Shizuo Tsubokura; Kunio Hoshino; Itsuo Takayanagi, all of Shizuoka, Japan

OTHER PUBLICATIONS

Connector in FIG. 2 of IBM Tech. Disclosure Bulletin, vol. 16, No. 12, 5-74.

[73] Assignee: Yazaki Corporation, Japan

Primary Examiner—Susan J. Lucas

[**] Term: 14 Years

Assistant Examiner—Joel Sincavage

[21] Appl. No.: 242,053

Attorney, Agent, or Firm—Jones, Askew & Lunsford

[22] Filed: Sep. 8, 1988

[57] CLAIM

[30] Foreign Application Priority Data

The ornamental design for a connector housing for a noise eliminator, as shown and described.

Mar. 10, 1988 [JP] Japan 63-9523
[52] U.S. Cl. D13/147
[58] Field of Search D13/123, 133, 146, 147; 439/353, 344, 357, 544, 550, 571, 572, 586, 587, 595, 603, 660, 682, 685, 686, 687, 695, 696, 701

DESCRIPTION

[56] References Cited

FIG. 1 is a perspective view of a connector housing for a noise eliminator showing our new design; FIG. 2 is a front elevational view thereof; FIG. 3 is a right side elevational view thereof, the left side elevational view thereof being a mirror image; FIG. 4 is a top plan view thereof; FIG. 5 is a bottom plan view thereof; FIG. 6 is a rear elevational view thereof; FIG. 7 is a cross-sectional view thereof taken along line 7—7 of FIG. 2; FIG. 8 is a cross-sectional view thereof taken along line 8—8 of FIG. 2.
